PERFUME OILS CONTAINING 2-METHYL-3-(3',4'-METHYLENEDIOXYPHENYL)-PROPANAL

Muus G. J. Beets and Harm Van Essen, Hilversum, Netherlands, assignors to International Flavors & Fragrances I.F.F. (Nederland) N.V.
No Drawing. Original application Jan. 29, 1959, Ser. No. 789,795, now Patent No. 3,008,968, dated Nov. 14, 1961. Divided and this application Jan. 19, 1961, Ser. No. 98,998.

Claims priority, application Great Britain, Feb. 11, 1958, 4,390/58

3 Claims. (Cl. 167—94)

This is a division of application No. 789,795, filed January 29, 1959, now Patent No. 3,008,968.

We have discovered that 2-methyl-3-(3',4'-methylenedioxyphenyl)-propanal of structure I is an outstanding olfactory ingredient in perfume-containing compositions:

It shows an exceptional tenacity. A strip of filter paper was moistened with 2-methyl-3-(3',4'-methylenedioxyphenyl)-propanal to which 10/00 of a normal anti-oxidant, e.g. hydroquinone, had been added and kept for two months in contact with air at room temperature. After this period the odor was still strong and undegenerated.

It has an excellent stability in pure form and in perfume compositions as well as in articles in which such compositions are used, such as soaps, cosmetics, powders and aerosol products. Although 2-methyl-3-(3',4'-methylenedioxyphenyl)-propanal has a very strong, interesting and definite odor, it is easy to blend into specific and widely varying types of perfumes in relatively large amounts. This is clearly demonstrated by the examples given below.

2-methyl-3-(3',4'-methylenedioxyphenyl)-propanal has not been described in the literature. Its lower homologue, piperonal-ethanal or 3-(3',4'-methylenedioxyphenyl)-propanal (II) is far less interesting. It has been obtained in small quantities by some authors (Fourneau and Tiffeneau, Comptes rendus 141 (1905), 663; V. Paolini, Gazz 42, I (1912), 30 and Atti della R. Accad. dei Lincei (5), 20 (1911), 940; E. mosettig, Ber. 62 (1929), 1274, but none of them mentions the odor.

Pure 2-methyl-3-(3',4'-methylenedioxyphenyl)-propanal has the following properties: n_D^{20} 1.5331; d_4^{20} 1.1637; boiling point: 128° C. at 3 mm. Hg. The semicarbazone, white leaflets from ethanol has a melting point (corr.) of 168.0° C. to 168.3° C.

2-methyl-3-(3',4'-methylenedioxyphenyl)-propanal may be prepared according to several methods of synthesis, as described in our copending application Serial No. 789,795, filed January 29, 1959, now Patent No. 3,008,968, for "Process for Making 2-methyl-3-(3',4'-methylenedioxyphenyl)-Propanal," of which this is a division.

The following examples illustrate perfume oils in which 2-methyl-3-(3',4'-methylenedioxyphenyl)-propanal is used

2

as an olfactory ingredient, in admixture with the indicated additional components in the given amounts:

Example I

A perfume oil having a cyclamen character was made by mixing together the following ingredients:

	Parts by weight
2-methyl-3-(3',4'-methylenedioxyphenyl)-propanal	50
Hydroxycitronellal	12
10 Linalool	4
Alpha ionone	5
Linalyl acetate	4
15 Geraniol ex Java citronella oil	3
Phenyl ethyl alcohol	5
Musk ketone	2
15 Amyl cinnamic aldehyde	5
Benzyl acetate	5
Terpineol	5

Example II

A perfume oil having a jasmin character was mixed from the following ingredients:

	Parts by weight
2-methyl-3-(3',4'-methylenedioxyphenyl)-propanal	50
25 Amyl cinnamic aldehyde	13
Benzyl acetate	10
Linalool	5
Linalyl acetate	5
Hydroxy citronellal	5
30 Heliotropin	4
Phenyl ethyl alcohol	8

Example III

A perfume oil having a rose character was mixed from the following ingredients:

	Parts by weight
2-methyl-3-(3',4'-methylenedioxyphenyl)-propanal	35
Geraniol ex Java citronella oil	18
Rhodinol	8
40 Phenyl ethyl alcohol	5
Hydroxy citronellal	5
Alpha ionone	5
Geranyl acetate	3
45 Aldehyde C ₁₁ , undecylenic	1

- What we claim is
1. A composition consisting of perfume oil and 2-methyl-3-(3',4'-methylenedioxyphenyl)-propanal.
  2. A composition consisting of a perfume oil, a fragrance-imparting proportion of 2-methyl-3-(3',4'-methylenedioxyphenyl)-propanal and perfume diluents.
  3. A composition consisting of a perfume oil having exceptional tenacity and a sufficient amount of 2-methyl-3-(3',4'-methylenedioxyphenyl)-propanal to impart the fragrance of the propanal to the oil, and a cosmetic carrier compatible with the propanal.
